SWITCHING MEANS FOR TRANSFORMERS

Willi Reiche and Walter Tesch, Dresden, Germany, assignors to Koch & Sterzel Aktiengesellschaft, Dresden-A. 24, Germany, a corporation of Germany

Application June 25, 1938, Serial No. 215,784
In Germany July 10, 1937

4 Claims. (Cl. 171—119)

This invention relates to switching means for transformers and refers more particularly to a device for regulating a step-transformer under load.

5 A step-transformer has a secondary winding which is tapped off at several points, so that it is possible by means of a switch to vary the voltage of the secondary circuit while the transformer is under load by varying that length of the secondary winding which is included in the secondary circuit.

Prior art constructions of this type have the drawback that the voltage drops twice in the course of the switching from one step or stage 15 to an adjacent one, and may even fall below the normal voltage of the step to which the transformer is being changed. Constructional changes which were carried out to eliminate this drawback resulted in an increase of the current flowing through the switch, with the result that the 20 contacting surfaces of the switch were quickly destroyed.

An object of the present invention is the provision of a step-transformer the secondary voltage of which can be easily changed while the transformer is being operated, without any substantial drop in voltage and/or without any substantial increase of the electrical current.

Other objects will be apparent in the course 30 of the following specification.

The objects of the present invention may be realized through the use of two change-over switches namely, a main switch and an auxiliary one, which are included in the secondary circuit of a step-transformer. Each switch has two operative final or end positions, and there is a pair of main contacts and a pair of advance contacts for each such position. Each main contact is connected to a separate advance contact 35 and the contacts of the auxiliary switch are connected without any substantial increase in resistance to the corresponding main contacts of the main switch. The main contacts serve for the transmission of the electrical current in the operative end positions of the switches, while advance contacts are included in the circuit only in the course of the switching from one stage to another. In accordance with the present invention the movable elements of the two change-over 40 switches are coupled in such manner that the main contacts remain open and do not participate in the transmission of the electrical current during the switching.

According to a preferred embodiment of the 45 present invention, in the course of the switching,

the current-transmitting main contacts of the two switches are first replaced in the circuit by the adjacent advance contacts, then the two pairs of advance contacts of the main switch are electrically connected with each other, and finally the two interengaging advance contacts of the auxiliary switch are separated, while shortly thereafter the other two advance contacts of the auxiliary switch are brought in contact with each other.

The invention will appear more clearly from the following detailed description when taken in connection with the accompanying drawings showing, by way of example, a preferred embodiment of the inventive idea.

In the drawings:

Figure 1 shows a device constructed in accordance with the principles of the present invention.

Figure 2 is a wiring diagram of the device for 20 regulating the one-phase step-transformer shown in Figure 1; and

Figure 3 is similar to Figure 2 and illustrates the various connections when the transformer is switched to the next stage or step.

The drawings show a transformer having an iron core 40 which carries the primary winding 41 of the transformer. The secondary winding 42, 43 comprises a non-adjustable portion 42 which is connected to the terminal 44 of a switch 45. The movable lever 46 of the switch 45 may be brought into engagement with either the positive terminal 47 or the negative terminal 48, which are connected to the opposite ends of an adjustable winding 43 constituting a part of the 35 secondary winding.

The primary and the secondary windings of the transformer are preferably situated in the casing 49, which is filled with oil. A secondary casing 50, which is in reality considerably smaller 40 than the casing 49, is situated upon the latter and is used as a container for the regulating device.

Two sequence switches 51 and 52 are provided with movable elements 53 and 54, respectively. 45 The element 53 of the sequence switch 51 is movable over contacts designated by the even numerals 2, 4, and 6, while the movable element 54 of the sequence switch 52 is movable over the odd contacts 1, 3, 5 and 7. The contacts 1 to 50 7 are connected with wires 55 to 59, which are connected to various parts of the winding 43, thereby subdividing this winding.

The terminal 56 of the sequence switch 51 is connected by a wire 57 with the terminal 58 of 55

the main switch 19. A wire 57 connects the terminal 56 with the terminal 58 of the auxiliary switch 20. A wire 59 connects the terminal 60 of the sequence switch 17 with the terminal 61 of the main switch 19, while the latter terminal is connected with the terminal 62 of the switch 20 by means of the wire 63.

The two sequence switches 19 and 20 are used alternately for the purpose of changing the operative length of the winding 13 by shifting from an odd step to the next even step and vice-versa. Any suitable mechanical or manually operated device 64 connects the two switches 16 and 17 and is so arranged that first one of these switches 15 may be moved to the extent of one contact and then the other switch is moved to that extent. The device 64 is preferably connected with the switch 18, which is moved from one of the contacts 42 or 43 to the other one of these contacts 20 after the sequence switches 16 and 17 have been moved over all the contacts. This movement of the switch 18 reverses the connection of the winding 13 with the winding 12. Due to this arrangement, the extent of the regulation is doubled, or in other words, it is possible to carry out a plus-minus regulation by means of the switch 18.

Of course, in certain constructions, the use of the switch 18 may be unnecessary and then one 30 end of the winding 13 may be connected directly with one end of the winding 12 or the two windings may be combined into a single one.

The main switch 19 has the form of a bent-lever joint and comprises a lever 21 which is 35 rotatably mounted at 65 and which is pivotally connected at 66 with one end of a link 22. The opposite end of the link 22 is pivotally connected at 67 with the lever 23, which is rotatably mounted at 68. One end of a spring 24 is connected with the element 22 while the opposite end of the spring is carried by a carriage 25. The carriage 25 carries an abutment or nose 26 which may be brought into engagement with the lever 23 in the course of the movement of 40 the carriage to the right from the position shown in Figure 2. The coiled spring 24 is brought under tension by this movement of the carriage 25. The purpose of the nose 26 is to move the leverage system consisting of the members 21, 22 and 45 23 out of its dead-end positions, in which the link 22 is in alinement with one of the levers 21 or 23. Due to the action of the nose 26, the spring 24 is able to move the link 22 and rapidly bring the leverage system into the opposite end 50 position. The lever 21 carries a conducting leaf spring 27 which supports an advance contact 69 and a main contact 70. The advance contact 69 is adapted to cooperate with the immovable advance contact 71 connected to one end of a 55 resistance 29, the opposite end of which is connected to the terminal 56. The main contact 70 is adapted to cooperate with an immovable main contact 72, which is connected to the terminal 56.

The same arrangement is substantially repeated on the opposite side of the switch 19. The lever 23 carries a conducting spring 28, which is provided with an advance contact 73 and a main contact 74 adapted to cooperate with the immovable advance contact 75 and the immovable main contact 76, respectively. The immovable contacts 75 and 76 are connected to the two ends of a resistance 30, and the conducting springs 27 and 28 are electrically connected with each other by means of the wire 90.

75 The auxiliary switch 20 is substantially simi-

lar in construction to the main switch 19 and comprises the levers 77 and 78 which are connected by the link 79 and which carry the spring 31 and 32, respectively. A coil spring 80 connects the link 79 with the carriage 81. The 5 spring 31 of the lever 77 carries an advance contact 82 and a main contact 83, which are adapted to be brought into engagement with the immovable advance contact 84 and the main contact 85, respectively. The spring 32 carried by the 10 lever 78 is provided with the advance contact 86 and the main contact 87, which are adapted to be brought into engagement with the immovable contacts 88 and 89, respectively.

A wire 33 which constitutes a continuation of 15 the secondary winding 12, 13 is electrically connected by means of the wire 90 with the conducting springs 27 and 28 and the movable contacts 69, 70, 73 and 74, which are carried by these springs. The wire 91 connects the wire 20 33 with the movable contacts 82, 83, 86, and 87 of the auxiliary switch 20.

Consequently, a pair of main contacts and a pair of advance contacts are provided for each operative position of each change-over switch. 25 The pairs of contacts 70 and 72; 74 and 76; 83 and 85; and 87 and 89 are designated as main contacts, since the contacts of one of these pairs are in engagement with each other in any end position of each change-over switch. On the other hand, the pairs of contacts 69 and 71; 73 and 75; 82 and 84; and 86 and 88 are designated as advance contacts, since they come into engagement with each other only in the course of the movement of the change-over switches from 30 one end position to another end position.

As already mentioned, the main contact 72 is connected with the advance contact 71 by means of the resistance 29, and is connected with the sequence switch 16 by means of the terminal 56 40 and the wire 55. Similarly, the main contact 76 is connected by means of the terminal 61 and the wire 59 with the sequence switch 17 and is connected by means of the terminal 61 and the wire 59 with the sequence switch 17 and is connected by means of the resistance 30 with the advance contact 75.

It is apparent that the auxiliary changeover switch 20 is substantially similar in construction to the main changeover switch 19. However, an 50 important distinction in the construction of the two switches is that the advance contact 84 of the auxiliary switch is connected with the main contact 85 of that switch not through any substantial resistance but by means of a wire 92 having 55 a very small resistance, while the advance contact 88 is connected with the terminal 82 and the main contact 89 by means of a wire 93 which also has a small resistance. On the other hand, the main switch 19 is provided with two resistances 29 and 30.

Any suitable mechanical device 94 known in the art is used for coupling the movable elements of the two switches 19 and 20 with a certain amount of play. The two carriages 25 and 81 of the switches 19 and 20 are driven together by the same mechanism which operates the sequence switches 16 and 17 and the reversing switch 18. The drive is carried out in such manner that the two changeover switches 19 and 20 are moved 70 from one of their end positions to the other end position after one of the two sequence switches 16 or 17 has been moved forward to the extent of one contact. Mechanical drives of this type are known per se in the art.

As already mentioned, the electrical connection of the change-over switches 19 and 20 is such that the main contact 85 of the auxiliary switch 20 is electrically connected by the wire 57 with the main contact 72 of the main switch 19 while the main contact 89 of the auxiliary switch 20 is directly connected by the wire 63 with the main contact 76 of the main switch 19. The wire 91 connects the movable leaf springs 31 and 32 of the auxiliary switch 20 with each other; the wires 91 and 33 and 90 connect the leaf springs 31 and 32 of the switch 20 with the leaf springs 27 and 28 of the switch 19. Thus the movable contacts 82, 83, 86 and 87 of the auxiliary switch 20 are connected with the movable contacts 69, 70, 73 and 74 of the main switch 19.

The leaf springs 31 and 32 of the auxiliary change-over switch 20 are somewhat differently located than the leaf springs 27 and 28 of the main change-over switch 19, since, as will appear from the following description, the pairs of advance contacts 84 and 82, and 86 and 88 of the auxiliary switch are not closed simultaneously and, in general, the contacts of the auxiliary switch 20 are closed somewhat later than the contacts of the main switch 19.

In the position illustrated in Figure 2, the movable lever 45 of the sequence switch 16 is situated upon the contact 4. In that position the current flowing through the secondary circuit of the transformer passes through the winding 12, the switch 18, the contact 42 and a portion of the winding 13 up to the point 4', flowing through the wire 50 to the terminal 4 of the sequence switch 16. Thence, the current flows through the lever 45 of the switch 16, the terminal 54 and the wire 55 to the terminal 56.

As shown in Figure 2, the contacts 70 and 72 of the switch 19 are in engagement one with the other, so that a portion of the current flows through these contacts and through the wire 90 to the wire 33. Since the contacts 83 and 85 of the auxiliary switch 20 are also closed, a portion of the current will flow through the wire 57 and the contact 58, and through the contacts 83 and 85 and the wire 91, which is connected to the wire 33.

Let it be assumed that it is desired to move the device one step forward from the step 4 to the step 5. This is carried out first by actuating the drive 64 and thereby moving the movable element 46 of the sequence switch 17, which at that time does not constitute a part of the electrical circuit, from the contact 3 to the contact 5. At the same time, the device 94 is actuated and causes the movement of the carriages 25 and 81 of the switches 19 and 20 from left to right (looking in the direction of Figures 2 and 3). The carriages pull at the springs 24 and 80, which are connected with them. The abutments of the carriages move the levers 23 and 78 out of alignment with the links 22 and 79, and then the springs 24 and 85 cause the leverage systems to spring rapidly into the opposite end positions shown in Figure 3, in which the other two pairs of main contacts 74 and 76, and 87 and 89 are in engagement with each other.

The following changes in the electrical circuit take place in the course of this rapid shifting of the movable elements of the switches 19 and 20 from one end position to the other end position:

At first, when the pairs of main contacts 70 and 72 and 83 and 85 are still closed, the advance contacts 71 and 69 of the main switch 19 are brought into engagement one with the other.

Then the electrical current flowing through the contact 4 of the sequence switch 16 and the wire 55 will be again subdivided at the terminal 56, a portion of the current flowing through the resistance 29 and the contacts 71 and 69 to the spring 27. Thus, the resistance 29 is switched into the circuit.

Shortly thereafter the advance contacts 82 and 84 of the auxiliary switch 20 are brought into engagement one with the other. This causes a division of the current at the terminal 58 of the switch 20, a portion of the current flowing through the wire 92 and the contacts 82 and 84 to the spring 31.

Then, the main contacts 83 and 85 of the auxiliary switch 20 are separated one from the other. At the same time, or shortly thereafter, the main contacts 70 and 72 of the main switch 19 are separated one from the other. Then the electrical current flowing through the contact 4 of the sequence switch 16 will flow along the wire 55 to the terminal 56, and from there a portion of the current will flow through the resistance 29 and the two contacts 69 and 71, the spring 27 and the wire 90 to the wire 33. Another portion of the current will flow from the terminal 56 through the wire 57, the terminal 58, the wire 92, the contacts 82 and 84, and the spring 31, joining the main circuit by means of the wire 91.

In the course of the further movement of the carriage 25, the advance contacts 73 and 75 of the main switch 19 are brought into engagement one with the other. At that time another electrical circuit, which includes the sequence switch 17, is brought into being. A portion of the electrical current will flow in the manner hereinbefore described, while another portion of the current will flow along the wire 13 to the point 5', which is the connecting point between the wire 13 and the wire 51 leading to the contact 5 of the sequence switch 17. This latter current will flow through the contact 5, the movable lever 46 and the terminal 60 of the sequence switch 17 and will then flow through the wire 59 to the terminal 61 of the resistance 70, passing through the contacts 75 and 73 and the spring 29 which is connected to the wire 90.

Shortly thereafter, the further movement of the carriage 81 will cause a separation of the advance contacts 82 and 84, so that at that time no current will flow through the auxiliary switch 20. In that position, the wire 33 is connected over the resistances 29 and 30 with both the contacts 4 and 5 of the sequence switches 16 and 17, while up to the time the contacts 82 and 84 were separated, the wire 33 was connected directly only with the contact 4.

Then in the course of the further movement of the switches, the advance contacts 86 and 88 of the auxiliary switch 20 will be brought into engagement one with the other, so that a portion of the electrical current will flow from the point 98, which is the connecting point between the wires 91 and 33, and through a portion of the wire 91 to the spring 32, passing through the contacts 86 and 88 to the wire 93, which is connected at 62 to the wire 63. This portion of the electrical current will joint the main circuit at the terminal 61. Thus the wire 33 is directly connected with the contact 5.

Shortly thereafter, the advance contacts 69 and 71 of the main switch 19 will be brought out of engagement one with the other. Then the switch 16 is excluded from the circuit, so that the electrical current flowing in the secondary circuit

through the switch 18 will flow along the wire 13 to the point 5' and will then flow through the wire 51, the switch 17, and the wire 59 to the resistance 30. Thence, the current will flow 5 through the advance contacts 73 and 75 and the spring 28 to the wire 93. At the terminal 98, a portion of the current will flow through the spring 32 and the advance contacts 86 and 88 of the auxiliary switch 20.

10 Thereupon, the main contacts 74 and 76 of the main switch 19 and the main contacts 87 and 89 of the auxiliary switch 20 will be brought into engagement. A portion of the electrical current will flow through the contacts 74 and 76, the wire 63 and the contacts 89 and 87 to the wire 91. 15 Another portion of the electrical current will flow from the terminal 62 through the wire 93 and the advance contacts 88 and 86 to the spring 32.

Finally, the advance contact 86 is moved away 20 from the contact 88 and the advance contact 73 is moved away from the contact 75. In this final position of the device, which is shown in Figure 3 of the drawings, the secondary electrical current flows through the wire 12 and the switch 18 to the point 5' of the winding 13, thence through the wire 51 and the contact 5 of the sequence switch 17 and through the wire 59 to the terminal 61. A portion of the electrical current flows through the main contacts 74 and 30 76 to the wire 33, while another portion of the electrical current flows from the terminal 61 through the wire 63 and through the main contacts 87 and 89 to the wire 91, which is connected at 98 with the wire 33. It is apparent that in this end position two pairs of main contacts 35 are in engagement.

If it is now desired to move from the contact 5 to the contact 6, the procedure is substantially 40 repeated. The sequence switch 16, which is not included in the electrical circuit, is actuated to move its lever 45 from the contact 4 to the contact 6, and thereupon the movable elements of the two switches 19 and 20 are shifted from right to left (looking in the direction of Figures 2 and 3).

45 It will be noted from the above description that an important advantage of the described construction is that the main contacts of the main switch 19 and the auxiliary switch 20, namely, the pairs of contacts 70 and 72, 74 and 76, 82 and 50 85, and 87 and 89 do not participate in the switching operation, which is carried out under load, but are open at that time, so that their contacting surfaces remain smooth and even. Only the auxiliary contacts of the two switches 19 and 20 take part in the switching operation, with the 55 result that there is no danger that the main contacts will be burned or deteriorated by the electrical current.

As shown in Figure 1, the switches 19 and 20 60 are preferably situated in one plane, one behind the other, and the auxiliary contacts of the two switches are situated above the main contacts adjacent the cover 34 of the casing 15 so that the auxiliary contacts are easily accessible whenever 65 the cover 34 is raised, and so that these auxiliary contacts can be easily removed and replaced by others whenever necessary.

As shown in Figure 1, it is advisable to use a 70 plate 99 consisting of cardboard or the like and to arrange the switches 19 and 20 upon one side of the plate, while the sequence switches 16 and 17, and preferably the reversing switch 18, are arranged upon the other side of the plate which extends in a vertical direction. The casing 15 is 75 preferably filled with oil as well as the casing 14.

If the device is used in connection with three-phase step transformers, then the windings necessary for the three phases may be arranged in a manner similar to the arrangement of the windings 12 and 13, while the three primary windings 5 which would correspond to the winding 11, may be interconnected in a star connection. Each phase must be provided with its own pair of sequence switches, a main change-over switch and an auxiliary change-over switch. However, the arrangement may be such that the conduits which correspond to the wire 33 and which are connected with the three main change-over switches and the three auxiliary change-over switches, are connected in the star connection. In fact, various 10 connections which are known per se can be applied to the regulating device constructed in accordance with the present invention. In the case of three-phase step transformers, it is advisable to 15 arrange the sequence switches and the reverse 20 switches in the common container, which is situated upon the casing of the transformer.

It is apparent that the specific illustrations shown above have been given by way of illustration and not by way of limitation, and that the 25 structures above described are subject to wide variation and modification without departing from the scope or intent of the invention, all of which variations and modifications are to be included within the scope of the present invention. 30

What is claimed is:

1. A switching device for step-transformers under load, comprising two sequence switches for the even and odd steps and a main change-over switch movable from one on position to another 35 on position and having for each on position separate main contacting means, separate advance contacting means and a separate resistance connecting said advance contacting means with said main contacting means, said device being characterized by the provision of an auxiliary change-over switch, in addition to said main change-over switch, said auxiliary change-over switch being movable from one on position to another on position and also having for each on position separate 40 main contacting means and separate advance contacting means, each of the contacting means having an immovable contact and a movable contact, the immovable contacts of each of the main contacting means and advance contacting 45 means of said auxiliary change-over switch being connected with each other and with the immovable contact of the corresponding main contacting means of said main change-over switch, the movable contacts of the two change-over switches 50 being coupled with each other and operating in such manner that the main contacting means of the two change-over switches, which transmit an electrical current when the change-over switches are in the on positions, are open during the 55 switching under load.

2. A switching device in accordance with claim 1, characterized in that only after the interruption of the connection of the contacts of the main contacting means of the two change-over switches 65 and the establishment of a connection of the contacts of the advance contacting means corresponding to the same on position of the change-over switches and after the main change-over 70 switch has provided a connection between its two advance contacting means, the connection of the contacts of the corresponding advance contacting means of the auxiliary change-over switch is interrupted and shortly thereafter the connection 75

of the contacts of the other advance contacting means is established.

3. In a switching device, in combination with a main change-over switch having two immovable main contacts, two immovable advance contacts, resistances connecting each advance contact to a separate main contact, two movable main contacts and two movable advance contacts, said immovable main contacts being adapted to be connected to a source of electrical energy; an auxiliary change-over switch having two immovable main contacts, two immovable advance contacts, two movable main contacts and two movable advance contacts, each of the immovable advance contacts of the auxiliary change-over switch being connected to a separate immovable main contact of that switch and to a separate immovable main contact of the main change-over switch; each of the two switches having two operative end positions, a separate immovable main contact of each switch engaging a movable main contact of that switch in each of said end positions; and separate conducting means movable from any one of said end positions to the other end position in the course of a switching operation for interrupting the engagement between the main contacts of each switch in the course of said switching operation, each of said conducting means carrying the movable contacts of its switch.
4. In a switching device, in combination with a main change-over switch having two immovable main contacts, two immovable advance contacts, resistances connecting each advance contact to a separate main contact, two movable main con-

tacts and two movable advance contacts, said immovable main contacts being adapted to be connected to a source of electrical energy; an auxiliary change-over switch having two immovable main contacts, two immovable advance contacts, two movable main contacts and two movable advance contacts, each of the immovable advance contacts of the auxiliary change-over switch being connected to a separate immovable main contact of that switch and to a separate immovable main contact of the main change-over switch; each of the two switches having two operative end positions, a separate immovable main contact of each switch engaging a movable main contact of that switch in each of said end positions; and separate conducting means movable from any one of said end positions to the other end position in the course of a switching operation for interrupting the engagement between the main contacts of each switch, providing an engagement between adjacent advance contacts of each switch, then providing an engagement between other advance contacts of the main change-over switch, then interrupting the engagement between the engaged advance contacts of the auxiliary change-over switch and shortly thereafter providing an engagement of the other advance contacts of the auxiliary change-over switch, each of said conducting means carrying the movable contacts of its switch and carrying out this movement in the course of said switching operation.

WILLI REICHE.
WALTER TESCH.
